(57) **CLAIM**

The ornamental design for a lounge chair, as shown and described.

DESCRIPTION

FIG. 1 is a perspective view of a lounge chair in accordance with the new design;

FIG. 2 is a front elevational view thereof;

FIG. 3 is a right side elevational view thereof, a left side elevational view being a mirror image thereof;

FIG. 4 is a rear elevational view thereof;

FIG. 5 is a top view thereof; and,

FIG. 6 is a front elevational view of an alternative embodiment of the lounge chair shown in FIGS. 1-5 with portions cut away to illustrate indeterminate width.

The broken lines in the figures are for illustrative purposes only and form no part of the claimed invention.
